Thos. S. Crane, Atty.

UNITED STATES PATENT OFFICE.

WILLIAM BAXTER, OF JERSEY CITY, NEW JERSEY.

PISTON.

SPECIFICATION forming part of Letters Patent No. 269,558, dated December 26, 1882.

Application filed February 10, 1882. (No model.)

To all whom it may concern:

Be it known that I, WILLIAM BAXTER, a citizen of the United States, residing in the city of Jersey City, in the county of Hudson and State of New Jersey, have invented certain new and useful Improvements in Pistons, fully described and represented in the following specification and the accompanying drawings, forming a part of the same.

10 My invention relates to an improvement in steam-pistons; and it consists in a special construction for the external packing-rings and the means employed for setting them out.

15 The object of my invention is primarily to produce a piston capable of moving securely over the edges of the ports entering a cylindrical steam-chest, and its construction is such that the outer packing-rings can be held rigidly after setting out, to adapt them to move 20 over such ports substantially as if solid.

A piston constructed as herein described is of course applicable to any cylinder, and may be used in a water-motor or the working-cylinder of any engine.

25 In the drawings annexed, Figure 1 is a view of the piston A with the follower B removed. Fig. 2 is a section on line *x* *x* in Fig. 1. Fig. 3 is an edge view of the external rings detached; Fig. 4, an edge view of the expanding ring, and Fig. 5 an outside view of the follower B; Fig. 6, a side and Fig. 7 a plan view of modified means for adjusting the packing.

A is the body of the piston; B, the follower, secured to the body by bolts C, as usual.

35 D is a hub, provided with a central hole, E, for the insertion of the rod.

F is an inner ring, cast upon the body, to support a continuous or solid conical ring, G.

40 H is a split expanding ring, made parallel upon the outside to fit the packing-rings I and turned with a taper upon its interior to fit the ring G. The ring I is shown formed of three annular sections fitted together at their adjacent edges by a tongue and groove, b, Fig. 2, 45 to prevent any slipping of one upon another transversely to their axis, each section being cut at *a* to permit expansion and the rings adjusted (and pinned together, if desired,) to keep the cuts at different parts of the circumference, 50 as usual. The rings F and H are preferably scraped a little looser when being fitted than

the packing-rings I, so that the latter may be clamped by the screwing of follower up to the head. The ring G is made sufficiently narrower than the ring H to permit it to move inside 55 the latter and expand it by the action of the opposed conical surfaces. To produce such movement, screws *f* are fitted to lugs *d*, attached to the interior of the ring G, and the heads of the screws are extended through the follower, 60 so as to be turned at pleasure from the outside. The heads of the screws are formed with a square, *h*, for that purpose, and a collar, *g*, provided upon the neck of the screw prevents it from moving endwise by contact with the 65 inside of the follower. To accommodate the lugs *d*, the ring F is formed with recesses *e*, and recesses *J* are also shown in the outside of the follower for the heads of the screws *C* and *f*.

70 From the above description it will be seen that the contact of metal is continuous from the solid ring F outward to the surface of the packing-rings, so that the piston is as firm when screwed up as if solid.

75 The great expense of grinding in solid piston-valves may be largely saved by fitting such pistons as the above in their place and expanding the same from time to time as the rings or cylinder wear. When thus applied 80 the wear can be fully compensated and great loss of steam saved, which is incurred by the use of solid valves after they have worn too small for their seats.

85 It is obvious that two annular sections could be used for the ring I; but with some sacrifice to the support secured to their several sections. Such an arrangement is shown at Fig. 6, where the several screws *f* are shown geared together to move in unison. The necks of the screws 90 are extended beyond the surface of the follower and provided with cog-wheels *i*. A cog-wheel, *j*, mounted upon a bolt, *k*, in the center of the follower, serves to gear all the wheels *i* together, and a head, *h*, is therefore provided 95 upon only one of the screws, by which they may all be turned equally and at the same time.

100 This attachment insures a uniform expansion of the packing-ring without any special attention from the operator. The cog-wheels are merely indicated in Fig. 7 by dotted circles. A simpler device for securing a uniform

rotation of the screws is shown in Fig. 5, where the head of one of the screws is marked with an arrow, *n*, and the margin of the recess *J* is provided with graduations *l*, by which the relative position of the several screws can be readily observed and their position accurately adjusted.

By applying the graduations *l* and arrow *n* to all the screws the operator would possess the means of turning them all uniformly.

I am aware that conical rings have been used before to set out packing-rings in a piston both in combination with springs and with set-screws tapped through the follower *B*, and I do not therefore claim such a device, broadly; but my construction presents several points of difference from any previously known, and as these points secure very material advantages in the use and satisfactory working of the piston, I consider them as valuable improvements upon former inventions. Thus the conical ring *G* is so constructed by me that it can be turned of a circular shape internally, and thus fitted snugly to a supporting-ring, *F*, which has not been heretofore used for such a purpose. The use of the ring *F*, formed rigidly upon the body-plate *A* and extending into contact with the follower, not only keeps the conical ring *G* concentric, but braces it to force outward strongly, and it thus makes the entire set of rings as solid and immovable as if integral with the head or body *A*. The provision of the tongue-and-groove joint *b* in the outer rings, *I*, also secures the same object and prevents any possible displacement of the separate rings in passing over ports or such an-

nular passages as are common in piston-valve chests. The provision of collars *g* upon the adjusting-screws *f* and the formation of the nut in the lugs *d* instead of in the follower *B*, as has been done heretofore, prevent any projection of the screws outside the piston, and thus enables the same to work closer to the heads of the steam chest or cylinder, and the whole construction thus affords a combination not only more perfect in its operation, but more suitable for certain purposes, than those heretofore made.

Having thus fully described my invention, it will be seen that my construction is adapted to produce a very firm packing for a piston, and that the latter can be adjusted with great ease and accuracy to fit the cylinder. I therefore claim the same in the following manner:

In a piston, the combination, with the follower *B* and the head *A*, having a supporting-ring, *F*, turned to fit the interior of a movable ring, and provided with recesses *e*, for the purpose set forth, of the conical movable ring *G*, provided with lugs *d*, and operated by the screws *f*, as described, the tapered and cut expanding ring *H* and the packing-ring *I*, formed of annular sections fitted together with tongues and grooves *b*, substantially as shown and described.

In testimony whereof I have hereunto set my hand in the presence of two subscribing witnesses.

WM. BAXTER.
